UNITED STATES PATENT OFFICE.

GEORGE FREDRICK WALTER, OF BROOKLYN, NEW YORK, ASSIGNOR TO AMERICAN CAN COMPANY, OF NEW YORK, N. Y., A CORPORATION OF NEW JERSEY.

METHOD AND APPARATUS FOR FORMING AN INTERIORLY BEADED OR LOOPED TEARING-STRIP CAN.

Application filed February 19, 1926. Serial No. 89,486.

My invention relates in general to a method and apparatus for forming an interiorly beaded or looped tearing strip can with a friction plug reclosure of the type and construction described, illustrated and claimed by John M. Young in his Patent 1,586,277, granted May 25, 1926. In this Young type of tearing strip container with friction plug reclosure, a portion of the container wall, 5 a short distance from the top edge, is looped inwardly and upwardly to provide, after said loop or bead has been properly finished and sized, an interior friction wall seat to be engaged by a corresponding interior friction 10 bead or plug formed on the inside of the container cover. Cans of this type have sanitary can ends double seamed to their top and bottom flanges. They also have parallel encircling score lines, with auxiliary score lines 15 between the parallel ones, setting off a tearing strip which terminates into a key engaging tongue. This tearing strip is located between the top double seam and the body bead or loop. When the tearing strip has been 20 removed by means of an opening key the severed container cover with the friction plug element is free to form a reclosure for the container by means of the frictional engagement between the interior can body bead or loop and the inwardly extending friction 25 plug portion of the severed can cover.

A specific object of my invention is the provision of a novel method and apparatus for forming said interior body bead or loop, 30 finishing it to desired shape and for bringing the formed bead or loop to true size or accurate diameter corresponding to the diameter of the friction plug.

The initial beading operation of the can body being the same as already described and illustrated in detail in my co-pending applications, Serial No. 89,277 and Serial No. 95,252, emphasis in the present application will be laid upon the novel method and apparatus of collapsing and sizing the body 45 bead or loop. It is most important in the manufacture of this type of container that the inner diameter of the inwardly bent looped portion which is later to form the friction wall seat be properly sized to correctly, tightly and uniformly engage the cover friction plug member when the latter is used as a reclosure after severance from the container by the removal of the tearing strip. This es-

sential truing and sizing condition is easily 55 accomplished by my method and by the mechanism which I have illustrated in the drawings. It should be understood that this mechanism represents only one form of my invention and I do not wish to limit myself to the 60 preferred embodiment shown herein.

One of the objects of my invention resides in providing a very simple and inexpensive method for manufacturing the type of container referred to in a manner that lends itself to commercial high speed production, 65 consisting of the least number of operations compatible with practical and efficient manufacturing principles.

Another object of my invention resides in 70 the provision of a novel method and apparatus for rolling the collapsed bead of a cylindrical body to exact size.

Still another object of my invention resides in the provision of a simple method and apparatus for rolling a peripheral bead in the cylindrical wall of a container body, in collapsing said bead by endwise pressure and thereafter rerolling said collapsed bead to exact size. 75

Numerous other objects and advantages of the invention will be apparent as it is better understood from the following description, which, taken in connection with the accompanying drawings, discloses a preferred 80 embodiment thereof.

Referring now to the accompanying drawings which form a part of the specifications,

Fig. 1 is a perspective view, with parts broken away, of the type of container adapted 85 to be formed according to my invention.

Fig. 2 is a longitudinal section through a portion of a beading device, this view illustrating a positioned container body being operated upon by the beading members. 95

Fig. 3 is a partial longitudinal elevation and cross section through a collapsing mechanism, the view illustrating the second or collapsing operation.

Fig. 4 is a view similar to Fig. 2 illustrating the completion of the forming of the bead or loop and the final accurate sizing of the same by a roller mechanism identical in construction and operation with the beading mechanism shown in Fig. 2. 100

Referring more in detail to the drawings and particularly to Fig. 1, the numeral 10 indicates a hollow container body of a cylindri-

cal or other form, provided with the ordinary side seam 11, and circumferentially scored lines 12 setting off a tearing strip 13, and further provided with directing score lines 14 arranged at an angle to the score lines 13. The said tearing strip 13 terminates in the tongue 15 extended beyond the said side seam 11. The container is provided with a bottom member 16 and a cover member 17 double seamed to the container wall. The said cover member 17 is provided with a counter-sink 18, inwardly spaced from the interior wall of the container 10 when the cover member 17 is secured to the seam by the regular double seam 19. The container wall 10 is inwardly pressed at 20 to form an upwardly and inwardly extending loop 21, connecting with a downwardly and outwardly extending loop 22, formed in the container wall adjacent and beneath the tearing strip 13. The inner diameter of the looped portion 21 is correctly sized to securely engage the outer diameter of the counter-sink 18 after the tearing strip is removed and when the cover member 17 is used as a reclosure for the opened container 10.

In forming the particular elements described in this container and shown in Fig. 1, it is necessary to first form the container body 10 in the regular manner by properly shaping it to cylindrical or other form and engaging the edges of the blank in the regular side seam 11. This cylindrical or other formed body 10 is then pressed in a beading machine where the first operation of forming the looped construction is accomplished. The forming of the first operation or bead on the container part is clearly illustrated in Fig. 2.

The beading mechanism consists of an inner beading roller 23 rotatably mounted on a stud 24 eccentrically secured to the end of a shaft 25, eccentrically journaled in a sleeve 26 rotatable within a shell 27. A hollow cup member 28 is threaded fixedly to the shell 27 and extends beyond the end of the same as clearly illustrated in Fig. 2. In the annular opening formed in the outer part of the shell there is disposed a ring 29 secured to the cup member 28 by means of screws 30, passing through a hardened steel washer 31 overlying the end of the sleeve 26 and spaced therefrom. The ring 29 is formed with an inwardly extended annular ridge 32 adapted to cooperate at certain periods with an annular groove 33 formed in the roller 23, as clearly illustrated in Fig. 2.

The formed cylindrical container body 10 is inserted within the beading device by being positioned with its inner end against the washer 31, it being understood that the sleeve 26 and the shaft 25 are moved relative to one another, in order, by reason of the eccentricity of each of those members, to position the roller 23 centrally of the ring 29 and away

from the inner wall of the ring 29. After the container body 10 has thus been positioned the shaft 25 and the sleeve 26 are both slightly rotated to force the roller 23 toward the inner wall of the ring 29, as illustrated in Fig. 2. In this position the roller 23 engages the inner diameter of the container body 10 and the groove 33 of the said roller forces the material of the container wall against the annular ridge 32 of the ring 29 and causes that part of the container wall to conform to the shape of the ridge 32 and the groove 33. While the sleeve 26 and the shaft 25 are then held in fixed position the shell 27 carrying the cup member 28 and the ring 29 is then rotated, which action causes the ridge 32 to contact the entire circumference of the container body 10 in a circular path of travel, and this action by reason of the cooperation of the roller 23 which works upon the stud 24 forms an inwardly pressed bead 35 into the upper wall of the container body 10 adjacent the tearing strip 13.

After the groove 35 has been formed entirely around the container body 10 the sleeve 26 and the shaft 25 are moved to cause the roller 23 to move inwardly from its position adjacent the ring 29 and thus to free the said container body 10. The formed and now beaded container body is then removed from the beading machine.

After this first or simple beading operation the formed and partially beaded container body 10 is then transferred to a collapsing and sizing or truing mechanism, illustrated in Figs. 3 and 4.

Referring now to Fig. 3 where the second or collapsing operation is shown, the can body is positioned upon a bed plate or base 36 which is a part of an organized apparatus, some of the common parts of which are not part of this invention and need not be shown. The collapsing device is then lowered over the top of the said body 10. This collapsing device consists of a hollow shell housing 37. Tightly but movably fitting within said shell housing 37 is a collapsing die or plunger member 38 fixedly secured to a plunger shaft or rod 39. The collapsing die plunger 38 is divided into two portions of varying diameter, the upper part 40 being of a diameter corresponding to the inside diameter of the shell housing 38 and snugly fitting the inner walls of the same and the lower part 41 of a diameter less than the inside diameter of the shell housing 38 and also less than the inside diameter of the can body top 10, the difference between the two diameters being just about equal to the thickness of the can body wall. The dividing line between the two parts of the plunger die 38 is formed by the die shoulder 42, against which the upper edge of the can body wall abuts and whereby said can body edge is stopped. When the container body 10 is positioned as illus-

trated in Fig. 3, the plunger shaft 39 carrying the collapsing die 38 is moved downwardly towards the bed plate 36 and this action collapses the bead 35 shown in Fig. 2 to the 5 looped form 43 shown in Fig. 3, that is to say, the pressure exerted upon the upper margin of the can body 10 by the shoulder part 42 of the collapsing die 38 presses that can body wall portion which lies between the 10 shoulder 42 and the bead 35 downward until the bead assumes the looped form 43 shown in Fig. 3. While the bead 35 is thus collapsed 15 around the outer upper wall part of the container 10, acts as an outer ring pad or supporting annular mandrel and helps to keep the upper part of the can body, which has to stand the brunt of the pressure of the collapsing die, from being bent out of its original shape.

Diverting our attention now to Fig. 4 it will be noted that this figure illustrates a mechanism for shaping the collapsed bead or loop 43 25 to final form and for truing or sizing the inner diameter of the bead or loop to exactly correspond with the diameter of the friction plug member 18 of the container cover. This final shaping and sizing is accomplished by a roller 30 mechanism identical in construction and operation with the initial beading mechanism disclosed in Fig. 2. This final shaping and sizing mechanism consists of a beading and sizing roller 44 rotatably mounted on a stud 35 shaft 45, which is eccentrically secured to the 40 end of a shaft 46, which in turn is eccentrically journalled in a sleeve 47 rotatable within a shell 48. A hollow cup member 49 is fixedly threaded to the shell 48 and extends beyond the end of the same as clearly illustrated in Fig. 4. In 45 the annular opening or recess formed in the outer cup part of the shell there is disposed a ring 50 secured to the cup member 49 by means of screws 51, one of which is shown in Fig. 4. These screws 51 pass through a hardened steel 50 washer 52 positioned between the bottom of the cup part of the shell 49 and the ring member 50 and said washer having its annular inner margin projecting over the shoulder of the cup member 49. The inner wall of the ring member 50 is perfectly straight and smooth, for the purpose of providing a straight and smooth annular supporting contact for the outer side of the can body wall 55 around the beaded part of the upper can body wall.

The partially looped cylindrical container body 10 is inserted within this final shaping and sizing device with its inner end or upper 60 edge resting against and being stopped by the washer 52, it being understood that the sleeve 47 and the shaft 46 are moved relative to one another, in order, by reason of the eccentricity of each of those members, to position the roller 44 centrally of the ring 50 and

away from the inner wall of the ring 50. After the container body 10 has thus been positioned the shaft 46 and the sleeve 47 are both slightly rotated to force the roller 44 toward the inner wall of the ring 50. In this position 70 the roller 44 engages with its straight portions 53 the straight portions of the upper inner container walls above and below the bead 43 and the concave or grooved part 54 of the roller 44 engages the inner diameter of the bead 75 43 and forces the portion engaged to assume the finished form 55 shown in Fig. 4 the configuration of said groove 54 being the exact counterpart or mold of the desired finished bead 55. While the sleeve 47 and the shaft 80 46 is then held in fixed position the shell 48 carrying the cup member 49 and the ring 50 is then rotated, which action causes the groove 54 to contact the entire circumference of the container body 10 and the bead 43 in a circular path of travel and this action by reason of the cooperation of the roller 44 which works upon the stud 45 completes the finished bead 85 55 over its entire circumference. At the same time said grooved part 54 owing to its accurately dimensioned annular concavity acts as the sizing medium and brings the finished bead to accurately sized diameter corresponding exactly with the diameter of the friction plug member 18 of the container cover. 90

After the finished bead or loop 55 has been formed and accurately sized entirely around the inner container body 10 the sleeve 47 and the shaft 46 are further rotated to cause the roller 44 to move towards the longitudinal 100 axis of the annular ring member 50 and thus liberate the said container body 10. The completely beaded and sized container body is then removed from the finishing and sizing mechanism. 105

It is thought that the invention and many of its attendant advantages will be understood from the foregoing description, and it will be apparent that various changes may be made in the form, construction and arrangement of the parts without departing from the spirit and scope of the invention, or sacrificing all of its material advantages, the form hereinbefore described being merely a preferred embodiment thereof. 110

I claim:

1. The method of forming a sized looped wall portion in a cylindrical body comprising forming inwardly the peripheral bead in the cylindrical wall of the body, collapsing the bead, and thereafter rolling the collapsed bead to accurate circumferential dimension. 120

2. The method described, comprising rolling a peripheral inwardly extending bead in the cylindrical wall of a container body, collapsing the bead and re-rolling the bead to exact size. 125

3. The method described, comprising forming inwardly a peripheral bead in the cylindrical wall of a body, collapsing the bead to 130

form a looped wall portion, and thereafter subjecting the collapsed bead throughout its circumference to the rolling action of a die to size said bead.

5. 4. In an apparatus of the class described, the combination of a support for one end of a tubular body, a collapsing head for the other end comprising a shell adapted to concentrically surround a portion of said tubular body 10 near the peripheral bead formed therein, a plunger in said shell, said plunger having means forming an annular seat for the reception of the end of the tubular body and having a concentrically situated portion adapted 15 to lie wholly within the upper end of said tubular body to brace it and means for moving said plunger toward said support and through said shell to exert end pressure on said tubular body to collapse the peripheral 20 bead formed therein.

5. In an apparatus of the class described, the combination of a support for one end of a tubular body, a collapsing head for the other end, comprising a shell sufficiently deep 25 to snugly receive a relatively wide portion of the end wall of a tubular body formed with a peripheral bead therein, a plunger in said shell and having two dimensions whereby to form an intermediate shoulder adapted to 30 receive the end of the tubular body there against, with the portion of the plunger of smaller diameter lying snugly within and supporting, the inner wall of the end of the tubular body, and means for shifting said 35 plunger through said shell and towards said support to press upon the end of the tubular body wall and to collapse the bead thereof.

6. In a device of the class described, the combination of an annular die having a

smooth inner surface and adapted to receive 40 the cylindrical wall of a container body having an inwardly projecting bead therein, a die roll operatively positioned adjacent said annular die, and provided with a peripheral 45 groove of predetermined cross section, and means for shifting said roll relatively to said annular die to permit the positioning of a tubular body between said annular die and roll and means for causing relatively rolling movement between said roll and die to roll 50 said bead.

7. In a device of the class described, the combination of an annular member adapted to receive one end of a tubular member, a roll associated therewith, means for shifting 55 said roll relatively to said annular die and means for causing relative rolling movement between said die and roll, said die and roll having cooperative die faces, one of which is smooth and the roll having a peripheral 60 groove of predetermined cross section.

8. In a device of the class described, the combination of a support, an annular die thereon, and provided with a smooth inner wall forming a die surface, a sleeve carried by said annular die, and a shaft eccentrically mounted in said sleeve, a roller mounted on said shaft within said annular die so as to shift relatively thereto on rotation of said sleeve, said roll having a peripheral die 70 groove therein, a stop member carried by said annular die to position the end of a tubular body having a peripheral bead inwardly projecting from the wall thereof, and means for causing relatively rolling movement between 75 said roll and die to shape said bead.

GEORGE FREDRICK WALTER.
